Frederick R. Gruner, Moline, and Roy F. Schwegler, Rock Island, Ill., assignors to Ametek, Inc., New York, N.Y., a corporation of Delaware

Filed Mar. 6, 1963, Ser. No. 263,143

17 Claims. (Cl. 230—117)

This invention relates to fans for exhaust systems and particularly to an improved double duct or dual duct fan assembly capable of withstanding exhaust gases at elevated temperatures.

Double duct fans are employed in exhaust systems for furnaces and the like, and usually comprise a housing forming part of a stack and having parallel paths of flow on each side of a central portion that is open to the atmosphere and in which portion a fan motor is mounted.

It often happens that during furnace charging periods, flames from the furnace extend into the stack and up through the double duct fan assembly. This causes excessive heating of the fan motor bearings, windings and other parts of the motor, tending to decrease its useful life.

The principal object of the invention is to provide a double duct fan arrangement that will be capable of withstanding high temperatures.

Another object of the invention is to provide such a fan in which atmospheric air is forcibly circulated between the motor and fan housing.

Still another object of the invention is to provide such a fan in which a radiation shield is provided between the motor and housing.

Still another object of the invention is to provide such a fan assembly in which the motor shaft supports, in addition to the main fan, an auxiliary fan for forcing atmospheric air through the space between the radiation shield and the housing.

A double duct fan assembly may comprise a main cylindrical housing having frusto-conical sections at each end so that it can be connected into a stack for a furnace or other exhaust system. The cylindrical portion may be provided with diametrically aligned, elliptical openings for receiving a hollow auxiliary housing extending through the cylindrical portion. The periphery of the auxiliary housing may be welded or otherwise securely fastened to the peripheral edges of the elliptical openings in the cylindrical housing. A plate may be mounted within the hollow auxiliary housing for supporting a fan motor with the axis of its output shaft lying along the longitudinal axis of the main housing.

In one aspect of the invention, a radiation shield may comprise two hollow, elliptical-shaped sections of less dimensions than those of the auxiliary housing. The walls of one side of the elliptical-shaped sections may be slotted so that when the sections are brought together, the slots receive the plate for the fan motor. Supporting clips may be provided for attaching the shield to the auxiliary housing.

In another aspect of the invention, the output shaft of the motor may support a main fan at the upper end of the upper frusto-conical portion and it may make a slight clearance with the walls of the main housing. Accordingly, when the motor is energized, the fan will draw the exhaust gases through the two parallel ducts formed by the auxiliary housing.

In still another aspect of the invention, the output shaft of the motor may also support auxiliary fan means between the radiation shield and the auxiliary elliptical housing member for circulating outside air between the radiation shield and the auxiliary housing member.

In still another aspect of the invention, the auxiliary

2

fan means may include blades arranged in a backward curved manner relative to the rotation of the fan and the radiation shield adjacent the auxiliary fan means may be provided with a flow controlling flange adjacent the auxiliary fan.

In still another aspect of the invention, baffle means may be provided within the main housing surrounding the motor shaft extension leading from the auxiliary housing member and the main fan.

10 The above, other objects and novel features of the invention will become apparent from the following specification and accompanying drawings which are merely exemplary.

In the drawings:

15 FIG. 1 is an end view of a double duct exhaust fan to which the principles of the invention have been applied;

FIG. 2 is an elevational view of the fan shown in FIG. 1;

20 FIG. 3 is an exploded perspective view of the radiation guard and motor which it is designed to protect;

FIG. 4 is a plan view of the auxiliary fan forming part of the invention;

FIG. 5 is a view looking in the direction of the arrows along line 5—5 of FIG. 4; and

FIG. 6 is a view of a modified form of the invention,

Referring to the drawings and particularly to FIGS. 1 and 2, the principles of the invention are shown as applied to a double duct fan including a main hollow, cylindrical housing 10 having flanges 11 and 12 at each end thereof that are connected to mating flanges on frusto-conical end portions 13 and 14. The ends of the frusto-conical portions 13, 14 may include flanges 15 and 16 for attachment to stack sections of an exhaust system.

The assembled main housing with its frusto-conical end sections may be provided with diametrically opposed elliptical openings 17 and 18 adapted to receive an elliptical housing member 19 that extends along a diameter of housing 10 completely through the same. The edges of the elliptical openings 17, 18 may be welded or otherwise hermetically sealed to the periphery of the elliptical member 19. The housing, therefore, comprises parallel spaced passages extending longitudinally through it for the passage of gases, and a central transverse passage 20 through the housing that is open at each end to the atmosphere.

45 A plate 21 may be fixedly mounted within the passage 20, and it may support an electric motor 22 with the axis of its output shaft 23 lying along the longitudinal centerline of the housing 10. The plate 21 may be welded to the housing member 19 or otherwise securely mounted within the passage 20. The motor 22 may be bolted to plate 19 by bolts 24.

The shaft 23 may have fixed to it an extension 25 that extends to a point adjacent the flange 15 of the section 13. A fan 26 may be fixed to shaft extension 25, and it may be of a diameter substantially equal to that of the end of section 13 adjacent flange 15, making a slight clearance with said section at that point. In order to prevent the hot exhaust gases from attacking the extension 25, baffle means 27 within section 13 may surround extension 25 and extend from housing member 17 to a point adjacent to the fan 26.

60 A radiation shield 28 may be mounted within the passage 20 between the motor 22 and the housing member 19. Referring to FIG. 3, the radiation shield 28 may include two complementary sections 29 and 30. The sections 29 and 30 include opposed sides 31 and 32 that conform generally to the form of the side walls of the housing member 19. Top and bottom plates 33 and 34 are connected to the side walls 31 and 32, and each plate 33 is provided with a semicircular recess 35 surrounded by a flange 36 having a smooth curved portion 37.

The side walls 31 of sections 29 and 30 may be provided with aligned slots 38 and 39 of a width to receive the plate 21 within passage 20. Accordingly, when sections 29, 30 are brought together within passage 20, their edges are permitted to abut each other with plate 21 passing through one side of the radiation shield 28, and the half-circular openings 35 close about the extension 24 to such an extent as to provide an annular passage 40 (FIG. 2) between the abutting flanges 36 and the extension 25.

Clips 41 may be permanently attached to the opposite ends of sections 29 and 30, and they are adapted to be connected to the opposite ends of housing member 19. The clips 41 are formed in a manner to space the radiation shield 28 inwardly of the housing member 19 in order to provide a passage 42 between the shield 28 and housing member 19 for the passage of air therethrough.

The extension 25 is adapted to have fixed to it an auxiliary fan 43 between the plates 33 of shield 28 and housing member 19. Referring to FIG. 4, the auxiliary fan 43 may comprise two half-circular disks 44 and 45 having upturned flanged portions 46, 47 that can be bolted together by bolts 48. Blades 49 may comprise angle members arranged in a backward inclined position relative to the direction of rotation of said fan and at equal intervals about the disks 44, 45. Baffle members 50, 51 may be mounted on plates 33 of shield 28 on each side of the fan 43 for a purpose to be described.

Referring to FIG. 2, energization of the motor 22 rotates fan 26, causing air to be sucked or passed through the two parallel passages within housing 10 on each side of the transverse through passage 29, thence past the baffle 27 and through fan 26. At the same time, fan 43 sucks outside air in through the two open ends of transverse passage 20 between motor 22 and shield 28, thence through annular passage 40, past flow-control contoured throat flange 37, thence radially outwardly along fan blades 49. Baffles 50, 51 direct the air around radiation shield 28, between it and housing member 19, thence outwardly from passage 20 near the bottom thereof as viewed in FIG. 2. Accordingly, a constant flow of outside air is forcibly circulated between the radiation shield 28 and the housing member 19 to maintain the temperature of the motor 22, its bearings, and its windings at a safe value regardless of the temperature of the exhaust gases passing through housing 10.

Referring to FIG. 6, the principles of the invention are shown as applied to a modified form of fan in which the motor 22 is provided with a drive shaft 52 that extends from the end of motor 22 opposite that from which shaft 23 extends. Shaft 52 may also be provided with an extension 53 surrounded by a baffle 54 similar to extension 25 and baffle 27 previously described. The extension 53 may fixedly support a fan 55 adjacent the flange 16 in the same way that fan 26 is mounted on extension 25 adjacent flange 15.

An additional auxiliary fan 56, similar to fan 43, may be fixed to extension 53 between the lower end of shield 28 and the housing member 19. The shield 28 is also provided with flanged flow control passages 37 at the two ends of the shield. In the embodiment of FIG. 6, energizing motor 22 causes fans 55 and 26 to suck or transport the air through the parallel spaced passages within housing 10 while fans 43 and 56 suck air from the passage 20, through flow control flange portions 37, thence radially outwardly and downwardly and upwardly, successively, within passage 42 between shield 28 and member 19, thence transversely of housing 10 to the atmosphere.

Although the various features of the double duct fan have been shown and described in detail to fully disclose two embodiments of the invention, it will be evident that changes may be made in such details and certain features may be used without others without departing from the principles of the invention.

What is claimed is:

1. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having output shaft means extending through the wall of said auxiliary housing member into said main housing member; main fan means connected to said output shaft means within said main housing member for sucking air through said spaced parallel passageways within said main housing member; a radiation shield within said transverse passage between said motor and said auxiliary housing member; and means for causing outside air to circulate over said motor and through the space between said radiation shield and said auxiliary housing member.

2. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having output shaft means extending through the wall of said auxiliary housing member into said main housing member; main fan means connected to said output shaft means within said main housing member for sucking air through said spaced parallel passageways within said main housing member; a radiation shield within said transverse passage between said motor and said auxiliary housing member; and auxiliary fan means connected to said output shaft means for sucking outside air through said transverse passage, over said motor and through the space between said radiation shield and said auxiliary housing member.

3. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having output shaft means extending through the wall of said auxiliary housing member into said main housing member; main fan means connected to said output shaft means within said main housing member for sucking air through said spaced parallel passageways within said main housing member; baffle means within said main housing member surrounding said output shaft means between said auxiliary housing member and said main fan means; a radiation shield within said transverse passage between said motor and said auxiliary housing member; and means for causing outside air to circulate over said motor and through the space between said radiation shield and said auxiliary housing member.

4. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having output shaft means extending through the wall of said auxiliary housing member into said main housing member; main fan means connected to said output shaft means within said main housing member for sucking air through said spaced parallel passageways within said main housing member; baffle means within said main housing member surrounding said output shaft means between said auxiliary housing member and said main fan means.

ceive said plate, said abutting ends also including flanged semicircular recesses adapted when said sections are in abutting relation to encircle said output shaft means; auxiliary fan means connected to said output shaft means for sucking outside air through said transverse passage, over said motor and through the space between said radiation shield and said auxiliary housing member; and baffle means on each side of said auxiliary fan means.

11. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having an output shaft extending from each end thereof through the walls of said auxiliary housing member in opposite directions and into said main housing member; separate main fans connected to each of said output shafts within said main housing member and arranged to suck air in one direction through said spaced parallel passages within said main housing member; a radiation shield within said transverse passage between said motor and said auxiliary housing member; and means for causing outside air to circulate over said motor and through the space between said radiation shield and said auxiliary housing member.

12. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having an output shaft extending from each end thereof through the walls of said auxiliary housing member in opposite directions and into said main housing member; separate main fans connected to each of said output shafts within said main housing member and arranged to suck air in one direction through said spaced parallel passages within said main housing member; a radiation shield within said transverse passage between said motor and said auxiliary housing member; and separate auxiliary fan means connected to each of said output shafts for sucking outside air through said transverse passage, over said motor and through the space between said radiation shield and said auxiliary housing member.

13. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having an output shaft extending from each end thereof through the walls of said auxiliary housing member in opposite directions and into said main housing member; separate main fans connected to each of said output shafts within said main housing member and arranged to suck air in one direction through said spaced parallel passages within said main housing member; baffle means within said main housing member surrounding said output shaft means between said auxiliary housing member and said main fan means; a radiation shield within said transverse passage between said motor and said auxiliary housing member; and means for causing outside air to circulate over said motor and through the space between said radiation shield and said auxiliary housing member.

14. A fan comprising in combination, a main housing member; an auxiliary housing member extending transversely through said main housing member and separating the main housing member into two parallel passageways,

ways, one on each side of said auxiliary housing member, and forming a transverse passage through said main housing member, said passage being open at both ends to the atmosphere; a motor mounted in said transverse passage having an output shaft extending from each end thereof through the walls of said auxiliary housing member in opposite directions and into said main housing member; separate main fans connected to each of said output shafts within said main housing member and arranged to suck air in one direction through said spaced parallel passages within said main housing member; baffle means within said main housing member surrounding said output shaft means between said auxiliary housing member and said main fan means; a radiation shield within said transverse passage between said motor and said auxiliary housing member; and separate auxiliary fan means connected to each of said output shafts for sucking outside air through said transverse passage, over said motor and through the space between said radiation shield and said auxiliary housing member.

15. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a motor mounted in said transverse passage having an output shaft extending from each end thereof through the walls of said auxiliary housing member in opposite directions and into said main housing member; separate main fans connected to each of said output shafts within said main housing member and arranged to suck air in one direction through said spaced parallel passages within said main housing member; a radiation shield within said transverse passage between said motor and said auxiliary housing member; separate auxiliary fan means connected to each of said output shafts for sucking outside air through said transverse passage, over said motor and through the space between said radiation shield and said auxiliary housing member; and baffle means on each side of said auxiliary fan means.

16. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the atmosphere; a vertically disposed plate mounted within said transverse passage; a motor mounted on said plate and including an output shaft extending from both ends of said motor, through the wall of said auxiliary housing member into said main housing member; separate main fans connected to the opposite ends of said output shaft within said main housing member, the blades of said fans being arranged to suck air in one direction through said spaced parallel passageways within said main housing member; a radiation shield within said transverse passage, said shield comprising aligned complementary sections adapted to be held in end abutting relation and having aligned spaced slots adapted to receive said plate, said abutting ends also including flanged semicircular recesses adapted when said sections are in abutting relation to encircle both opposite extending portions of said output shaft; and means for causing outside air to circulate over said motor and through the space between said radiation shield and said auxiliary housing member.

17. A fan comprising in combination, a main housing member; an auxiliary housing member extending transversely through said main housing member and separating the main housing member into two parallel passageways, one on each side of said auxiliary housing member, and forming a transverse passage through said main housing member, said passage being open at both ends to the

atmosphere; a vertically disposed plate mounted within said transverse passage; a motor mounted on said plate and including an output shaft extending from both ends of said motor; through the wall of said auxiliary housing member into said main housing member; separate main fans connected to the opposite ends of said output shaft within said main housing member, the blades of said fans being arranged to suck air in one direction through said spaced parallel passageways within said main housing member; a radiation shield within said transverse passage, said shield comprising aligned complementary sections adapted to be held in end abutting relation and having aligned spaced slots adapted to receive said plate, said abutting ends also including flanged semicircular recesses adapted when said sections are in

abutting relation to encircle both opposite extending portions of said output shaft; and separate auxiliary fan means connected to the opposite extending portions of said output shaft for sucking outside air through said transverse passage, over said motor and through the space between said radiation shield and said auxiliary housing member.
